BRUSHING MACHINE FOR TREATING
STRIP MATERIAL

John C. Ruffer, Toledo, Ohio

Application October 20, 1944, Serial No. 559,630

1 Claim. (Cl. 15—77)

1
This invention relates to the continuous handling for treating attention of strip stock or material.

This invention has utility when incorporated to act simultaneously upon opposite sides of the work during its relative progress. More specifically, in applying the treating action by rotary means, as brushes, with the strip major portion at one side of the common axis between opposing brushes, the brushes rotating in the same direction, there results not only the cleaning or treating action upon the strip portion, but a travel thereof past the brushes.

Referring to the drawings:

Fig. 1 is a plan view of an embodiment of the invention as adapted for treating or cleaning a succession of Venetian blind slats or strips;

Fig. 2 is a side elevation, with parts broken away, of the Venetian blind strip cleaning machine of Fig. 1;

Fig. 3 is a fragmentary view, on an enlarged scale, showing the position of a strip as to a rotary brush, with the brush rotation to effect strip transit therepast; and

Fig. 4 is a partial section on the line IV—IV, Fig. 2, for the kick-off or discharge of the washed strips from the machine of Fig. 2.

Legs 1 support a table 2 having therebelow a platform or deck 3 upon which is mounted a prime mover or electric motor 4 with speed reduction belt gearing 5 effective thru stepped pulley 6 for variable speed reduction driving a wheel 7 fixed on shaft 8 mounted in bearings 9 on the table 2 near one end thereof. The direction of rotation of the wheel 7 is for its upper side to move away from its end of the table 2. This is in a clockwise direction in looking at Fig. 2.

In the set-up for the equipment as herein disclosed for washing or treating Venetian blind strips, there is located in the table top 2, and extending from below the shaft 8 away from such end of the table 2, a vat, tank, or reservoir 10. The tank 10 has an open top and may be charged with a washing solution 11. As such becomes dirty, requiring removal or replacement with some other substance for treating, a valve 12 may be opened and a portion or all drawn off by way of a pipe 13, extending to a sewer, waste, or a place for collection and retention for reclamation or other use as may be appropriate. When the strips to be treated have not become coated with hardened grime, a soap and water, or other mild detergent treatment solution 11 may be in order.

Partitioned away, or spaced from the tank 10, for rinsing or subsequent supplemental treatment, 15

there may be a vat or tank 14 equipped with a discharge valve 15 to a draw-off line 16.

For Venetian blind strips 17, a line of travel medially and lengthwise of the table 2 over the vats 10, 14, is established, having anti-friction hold-down means therealong as grooved pulleys 18 having height adjustable mounting brackets 19 therefor. There is thus provided means for taking care of a range of different width slats 17 to have the upper edge thereof direct such slats 17 for the lower edge to ride over the shaft 8 and therefrom in a plane parallel to the top of the table 2. The strip stock or slats 17 are thus held on-edge for a straight line of travel from end-to-end of the table 2.

Transmission from the shaft 8 as the main drive shaft is herein shown as belt gearing 20, 21, for additional shafts 22, 23, parallel to the shaft 8, and extending over the wash water vat 10. Additional belt gearing 24 drives shaft 25, also parallel to the shaft 8, but extending over the rinse water vat 14. Belt gearing 26 from the shaft 25 drives parallel shaft 27 also over the vat 14.

Each of these shafts 8, 22, 23 over the vat 10, and shafts 25, 27, over the vat 14, have thereon a pair in opposing relation of approximately flat faced circular brushes 28, desirably having a radial extent from the respective shafts at least fully that of the width of the slats 17 to be treated. This means that as the slats 17 ride to or contact the upper sides of the several shafts 8, 22, 23, 25, 27, in their transit thru the Venetian blind slat washing machine, the upper edge portions of the five pairs of brushes 28 are higher than the upper edge of the slats 17. The brush rotation thereby effects flexing of the brush fibers over the top edge of the slats 17 to insure effective treating attention here; while the major portion of the brushes as below the lower edge of the slats 17 likewise give cleansing attention thereto. Accordingly all sides of the slats are simultaneously given full washing action.

Between the brushes 28 on the shaft 23 and the adjacent end of the vat 10, there is located a pair of upright wipers or squeegee members 29 having adjustable mounting means 30 for toward each other and up and down shifting in properly locating this treating means to adequately contact the work for the removal of excess water or other substance and have such not go to the succeeding rinsing tank 14, but be returned to the tank 10 from which it may have been lifted by the partially submerged brushes 28 extending into the treating solution 11.

Rinsing solution 31 from the vat 14 may now

be brought by the brushes or rotary treating means 28 to act upon the washed strip 17. Beyond the shaft 27, and above the vat 14, is an additional pair of wipers or squeegee means 32, also having mounting means 33 for varying the height location thereof above the table top 2, as well as the spacing therebetween. There is thus also provided here a range of adjustment for thickness and width variations in the dimension of the strip stock to be handled.

Upon the table top 2 a short distance beyond the wipers 32, journal bearings 34, are yieldably thrust by compression helical springs 35 away from the table top 2. The bearings 34 mount a shaft 36 having set screw anchored collars 37 thereon in slight lateral clearance as to grooved pulley 38 therebetween. There is thus provided a yieldable upward thrust mounting for the antifriction means or roller 38 upon which the lower narrow edge of a slat 17 may ride to be upwardly thrust into the groove of an opposing grooved wheel 39. The side play allowable for the pulley 38 and the groove width for the wheel 39, automatically compensate to adapt to any warp, weave, twist, or other variation in the stock being handled. The strip travel from the pair 38, 39, is for discharge from the machine by riding over grooved pulley 40 mounted on table extension bracket 41.

From the shaft 27 there extends reverse direction or cross-belt gearing 42 to shaft 43 mounting the pulley 39. The direction of rotation of the wheel 39 is thus opposite to that of the several brush pairs 28. The periphery of the wheel 39 being larger than the overall diameter of the brushes 28, imparts a speed-up for the lower side of the wheel 39 in its counter-clockwise rotation as viewed in Fig. 2, to accelerate the pulling away of a final slat 17 from the squeegee pair 32, and delivery past the roller 40.

In operation, the slats, as on edge, are fed under the initial or first hold-down pulley 18 and over the shaft 8. At once, there is an automatic pick-up of the strip 17 between the first brush pair 28. The wide range of departure from constant lineal contact of the brush fibers with the strip, insures relative movement as the major factor. There is accordingly a resultant scrubbing response.

With the brushes 28 running some 8" to 9" in diameter, and the shafts imparting speed of around 250 R. P. M., 20 to 30 lineal feet of slats 17 may be propelled as to but two brush pairs. While slat feeding into the machine may be for abutting ends, the plural brush pair pickup increases from a first gap 44 to a wider gap 45.

While the yieldable mounting for the directing roller 38 introduces a variable to accommodate some range in width departures for the slats 17, further compensation may be introduced thru adjustable bearings 46, thereby to vary the spacing of the shaft 43 from the top of the table 2.

The brushes 28 are shown as of generally flat face, more or less stiff fibers. Departures in the selection thereof may be made to meet the special work undertaken. Even in the specific instance of Venetian blind slats, at times such may be in undesirable shape, as from plaster, paint, and grime, or attacking fumes. In practice for the normal cleaning, from domestic or household, as well as office building slats, a single pair of washing brushes, with a single pair of rinsing brushes, and the squeegees, will perform a satisfactory laundry job. Without additional brushes, there may be speed variation, to supplement the washing action as more dirty slats are to be handled.

5 The proximity, or closeness of setting of the brushes of a pair, thereby to hug together more closely, is also a feature of adjustment on the common shaft therefor. By disconnection of one or more of the follower belt gearings, the plural pair of brushes may be reduced in working number to fulfill the particular job in hand.

10 By considering the working face providing means 28 for treating purposes, the constitution thereof may respond for direct abrasive action. Again, the slats may be treated, as with varnish 25 or paint remover agents, as well as given handling for refinishing, as by filling, staining, varnishing, enameling, or painting.

15 While this handling of Venetian blind slats 17 is discussed as apart from assembly, there may be the handling before initial assembly. Furthermore, from assembly, provision may be made to take out and replace, thereby avoiding attack to the tape and cords.

20 30 35 What is claimed and it is desired to secure by Letters Patent is:

30 Slat brushing apparatus comprising a plurality of generally horizontally disposed shafts, said shafts being in the same general plane, a pair 40 of disk brushes mounted on each of said shafts, the working faces of said brushes being in opposed relation and closely spaced to treat a slat therebetween and propel the same, said brush pairs being in the same general vertical plane, 45 grooved guide rollers rotatably mounted on axes generally parallel to said shafts, said guide rollers being located in the same general vertical plane as said brushes, said rollers being located in close proximity to said brushes, whereby a slat to be 50 treated is positioned by said rollers and said pairs of brushes, and means to rotate said brush shafts.
